(21) Appl. No.: **29/582,074**

The ornamental design for a combined shaving razor handle and suction cup, as shown and described.

(22) Filed: **Oct. 25, 2016**

DESCRIPTION

(51) **LOC (11) Cl.** **28-03**

FIG. 1 is a first perspective view of a combined shaving razor handle and suction cup according to an embodiment of the invention.

(52) **U.S. Cl.** USPC **D28/48**; D6/526

FIG. 2 is a second perspective view of a combined shaving razor handle and suction cup of FIG. 1.

(58) **Field of Classification Search**

FIG. 3 is a right side view of the combined shaving razor and suction cup of FIG. 1.

USPC D28/46-48; D6/526
CPC B26B 21/08-21/32; B26B 21/02-21/06;
